PICTURE FRAME

Albert Babitz, Bayonne, N. J.

Application June 9, 1950, Serial No. 10,430

Term of patent 7 years

(Cl. D29—20)

To all whom it may concern:

Be it known that I, Albert Babitz, a citizen of the United States, residing at Bayonne, in the county of Hudson and State of New Jersey, have invented a new, original, and ornamental Design for a Picture Frame, of which the following is a specification, reference being had to the accompanying drawing, forming part hereof.

In the drawing:

Fig. 1 is a perspective view of a picture frame, showing my new design;

Fig. 2 is a vertical sectional view, taken on line 2—2 of Fig. 1; and

Fig. 3 is a rear elevational view of the same.

I claim:

The ornamental design for a picture frame, as shown.

ALBERT BABITZ.
